The ornamental design for a holiday display with miniature ferris wheels, as shown and described.

DESCRIPTION

FIG. 1 is a perspective view of a holiday display with miniature ferris wheels showing our new design;

FIG. 2 is a front elevational view of the base module, shown separately for clarity of illustration;

FIG. 3 is a left side elevational view of FIG. 2;

FIG. 4 is a right side elevational view of FIG. 2;

FIG. 5 is a top plan view of FIG. 2;

FIG. 6 is a bottom plan view of FIG. 2;

FIG. 7 is a rear elevational view of FIG. 2;

FIG. 8 is a top plan view of the first ferris wheel, shown separately for clarity of illustration;

FIG. 9 is a front elevational view of FIG. 8;

FIG. 10 is a right side elevational view of FIG. 8;

FIG. 11 is a left side elevational view of FIG. 8;

FIG. 12 is a rear elevational view of FIG. 8;

FIG. 13 is a bottom plan view of FIG. 8;

FIG. 14 is a top plan view of the second ferris wheel, shown separately for clarity of illustration;

FIG. 15 is a front elevational view of FIG. 14;

FIG. 16 is a right side elevational view of FIG. 14;

FIG. 17 is a left side elevational view of FIG. 14;

FIG. 18 is a rear elevational view of FIG. 14;

FIG. 19 is a bottom plan view of FIG. 14;

FIG. 20 is a top plan view of the third ferris wheel, shown separately for clarity of illustration;

FIG. 21 is a front elevational view of FIG. 20;

FIG. 22 is a right side elevational view of FIG. 20;

FIG. 23 is a left side elevational view of FIG. 20;

FIG. 24 is a rear elevational view of FIG. 20; and,

FIG. 25 is a bottom plan view of FIG. 20.
